UNITED STATES PATENT OFFICE.

JOHN RALSTON, OF SLIPPERY ROCK, PENNSYLVANIA.

ANIMAL-HOLDING APPARATUS.

SPECIFICATION forming part of Letters Patent No. 589,615, dated September 7, 1897.

Application filed March 29, 1897. Serial No. 629,687. (No model.)

To all whom it may concern:

Be it known that I, JOHN RALSTON, of Slippery Rock, in the county of Butler and State of Pennsylvania, have invented a new and Improved Animal-Holding Apparatus, of which the following is a full, clear, and exact description.

This invention is an apparatus for holding sheep during the operation of shearing them, and it is broadly characterized by an adjustable table on which the animal is situated between devices for holding the legs of the animal.

This specification is the disclosure of one form of my invention, while the claims define the actual scope of the conception.

Reference is to be had to the accompanying drawings, forming a part of this specification, in which similar characters of reference indicate corresponding parts in all the figures.

Figure 1 is a perspective view of the invention. Fig. 2 is a plan view thereof, and Fig. 3 is an elevation showing parts broken away and in section.

The apparatus has a base-plate *a*, whereon stands a stub-shaft *a'*, inclosed by a tubular column *b*, to which the vertical plate *b'* is rigidly attached. The upper edge of the plate *b'* is ratcheted and curved in the arc of a circle. Coextensive with the center of the circle of which said arm is a part is a pivot *c'*, pivotally connecting the two plates *c* with the plate *b'*. The plates *c* lie, respectively, on opposite sides of the plate *b'* and are rigidly attached to the table *d*, to which table the plates *c* are at right angles. The table carries a spring-pawl *b''*, pressing against the ratchet-teeth of the plate *b'*. This construction mounts the table, so that it may be turned on the shaft *a'* to any axial position and so that it may be given any inclination and be retained by means of the pivot *c'* and the pawl *b''*.

Each end of the base-plate *a* has means for holding, respectively, the front and hind legs of the sheep, these two means being duplicates of each other. Each consists in an angle-plate *e*, one member of which is rested on the base-plate *a* and held thereto by a fastening device *e'*, working in a slot *e''* in the said member of the angle-plate. The second mem-

ber of each angle-plate *e* is vertical and has a slot *e''*, in which fastening devices *f'*, respectively, operate. Each fastening device *f'* carries pivotally two vertically-extending arms *f*, the upper end of each of which is bent inward, forming a plate *f''*, which is provided with a padded slot *f'''*. These four padded slots *f'''* are designed to respectively hold the legs of the sheep. The legs are locked in place by pivoted bars *f''*, held in closed position by lynch-pins *f'''*. The arms *f* may be adjusted freely to regulate the position of the sheep.

In using the apparatus the sheep is placed on the table *d* with its legs secured by the devices on the arms *f*. The sheep is thus held effectively and humanely.

Having thus described my invention, I claim as new and desire to secure by Letters Patent—

1. An animal-holding apparatus, having a base, a stub-shaft standing on the base, a hollow column revolvably inclosing the stub-shaft, a table pivotally supported by the hollow column, arms pivotally mounted on the base-plate, and means carried by the arms, whereby the legs of the animal are held. 75

2. An animal-holding apparatus, having a base-plate, a table mounted on the base-plate, an angle-plate adjustable on the base-plate, 80 an arm adjustably pivoted on the angle-plate, and means carried by the arm and capable of holding one leg of the animal.

3. An animal-holding apparatus having a base-plate, a ratchet-plate mounted to turn 85 on the base-plate, a table, a plate pivoted to the ratchet-plate and fixed to the table, and a pawl carried by the table and engaging the ratchet-plate.

4. An animal-holding apparatus having a 90 base-plate, a slotted angle-plate carried on the base-plate, a pivot adjustable in the slot of the angle-plate, an arm swinging on the pivot, and means on the arm for holding one leg of an animal.

5. An animal-holding apparatus having a base-plate, two pivotally-mounted arms supported on the base-plate, and holding devices respectively carried by the arms and adapted to hold two legs of an animal, whereby the 100

legs may be moved toward and from each other by the adjustment of the arms on their pivot.

6. The combination of a base, a column standing on the base, a table supported by the column, two angle-plates adjustable on the base and respectively arranged at the sides of the table, and two arms pivoted to

each angle-plate, the arms of each angle-plate swinging on a common center and each arm being capable of holding the leg of an animal.

JOHN RALSTON.
